2,575,850

VALVE FOR AIR BRAKE CONTROL

Frank S. Swickard, Denver, Colo.; Laura Janette Swickard administratrix of said Frank S. Swickard, deceased

Application April 12, 1948, Serial No. 20,541

8 Claims. (Cl. 137—144)

1

This invention relates to railway air brakes and more particularly to an electrically controlled car valve unit to be placed on each individual car of a train which will operate simultaneously and uniformly throughout the length of the train. With the conventional air brakes on long trains the brakes at the front of the train apply in advance of the application at the rear thereof. This is due to the fact that the triple-valve of each car is dependent for its operation on the drop in pressure on the brake pipe. It is obvious that the drop in pressure in the brake pipe will commence at the locomotive and then follow to the rear end of the train due to air friction in the brake pipe.

The principal object of this invention is to provide an electrically controlled magnetically-operated car valve unit on each car, all of which will operate to admit air from the auxiliary reservoirs of the cars to the brake cylinders thereof simultaneously throughout the length of the train so that a uniform braking effect will be obtained throughout the length of the train at all times.

With the conventional air brakes the loss in pressure in the brake pipe after an application of the brakes must be replaced before the brakes can be released. In replacing this pressure the same delay occurs in the time of release between the front of the train and the rear thereof, that is, the pressure builds up first at the locomotive extremity of the brake pipe and this increase in pressure follows through to the rear of the train, thus causing the brakes to be released at the front of the train more rapidly than at the rear thereof. In long trains this creates great stress on the couplings which occasionally causes the train to pull apart.

Another object of this invention is to provide a car valve unit which will not be dependent upon variations in pressure in the brake pipe so that no time lag is encountered and so that the brakes on all cars regardless of the train length will release simultaneously.

When the conventional air brake system is in the "lap" position the pressures in the brake cylinders throughout the length of a train will vary due to the varying strokes of the brake pistons on the cars. That is, the longer stroke cylinders will have less pressure due to the greater expansion.

A further object of this invention is to provide a unit with a pneumatically and automatically operating lap device which will assure an absolutely uniform pressure in the brake cylinders of all of the cars of a train, regardless of the length of the stroke.

Delays in brake operation and release in long trains are aggravated by friction in the moving parts of the valve. A still further object of this invention is to provide a brake control car valve

2

unit in which friction on the moving parts will be reduced to a minimum.

With these and other objects in view the invention will now be described more in detail reference being had to the accompanying drawings, which form a part hereof.

In the following detailed description of the invention, reference is had to the accompanying drawing which forms a part hereof. Like numerals refer to like parts in all views of the drawing and throughout the description.

In the drawing:

Fig. 1 is a longitudinal section through the improved electrically controlled magnetically operated car valve unit; illustrating it in the running position;

Fig. 2 is a cross section taken on the line 2—2, Fig. 1;

Fig. 3 is a side view of the unit;

Figs. 4, 5 and 6 are cross sections taken on the lines 4—4, 5—5 and 6—6, respectively, Fig. 1;

Fig. 7 is a detail section through a double valve employed in the improved unit; and

Fig. 8 is a circuit diagram illustrating a train circuit for controlling the improved valve units.

The improved valve unit employs two cylindrical flanged shells which will be herein designated as an upper shell 10 and a lower shell 11 separated by a valve housing 15. An end plate 12 closes the lower extremity of the shell 11. The end plate 12 is secured to the lower flange of the shell by means of suitable clamp bolts 13. The upper extremity of the shell 11 has a conical projection 14 which fits into a conical seat in the bottom of the valve housing 15.

The shell 10 rests upon the valve housing 15 and the three members 10, 11 and 15 are clamped together by means of clamp bolts 16 which pass through a bottom flange on the shell 10, entirely through the peripheral edge of the housing 15; and through a flange 18 which surrounds the shell 11 below the top thereof.

The top of the shell 10 is closed by means of a cylinder plate 19 and the cylinder plate 19 is closed by means of an end plate 20. The plates 19 and 20 are clamped to the shell 10 by means of clamp bolts 21 passing through an upper flange on the shell 10 and entirely through the plates 19 and 20.

A hollow cylindrical solenoid coil 22 is mounted within the shell 10 and a similar solenoid coil 23 is mounted within the shell 11. The coil 22 surrounds a field core 24 of soft iron or other magnetically permeable material. The coil 23 surrounds a similar core 25. The cores 24 and 25 are formed on or secured to the cylinder plate 19 and the end plate 12, respectively.

A piston rod 26 is axially and slidably mounted in the core 24. The rod 26 is threaded into a magnetic armature member 29. The armature is

formed with a conical top which fits within a conical socket in the core 24. Annular sealing gaskets 27 surround the rod 26 at the points where it enters and leaves the core 24.

A piston 30 is mounted on the upper extremity of the piston rod 26 and operates in a pressure cylinder 31 formed in the cylinder plate 19. The piston 30 is provided with suitable sealing rings 32 which seal it to the walls of the cylinder 31. A bleed passage 28 leads from below the piston in the cylinder 31. A tapered valve 33 is threaded into or otherwise secured on the lower face of the armature 29. The valve 33 is positioned to close against the upper seat of a double valve seat 34. A compression spring 35 is positioned between the seat 34 and the armature member 29 and constantly urges the latter away from the seat 34.

The seat 34 is positioned between an auxiliary air passage 36 and a cylinder air passage 37. The passages 36 and 37 are formed in the valve housing 15 and are preferably internally threaded at their extremities to receive an auxiliary air pipe 38 and a cylinder air pipe 39 respectively.

A valve stem 40 extends within the second solenoid 23 and is threaded into a second armature member 41 having a conical lower extremity which fits within a conical socket in the core member 25. An axial spring socket is formed in both the core member 25 and the armature member 41 and contains a compression spring 43 which constantly urges the armature member 41 away from the core member 25. The armature members 29 and 41 are loosely fitted within their respective solenoid coils and are not air-tight therein.

A double valve 44 is mounted on the upper extremity of the stem 40. This valve has two seating faces. One of which is adapted to seat against the lower seat of the double valve seat 34 and the other of which is adapted to seat against an exhaust valve seat 45. The double valve 44 is tiltably mounted on the stem 40. The latter having a flanged extremity extending into a socket in the valve 44 and being maintained therein by means of a spring 46 compressed in a bushing 47 which is threaded into the double valve 44. This allows the valve 44 to tilt to accommodate itself to either of the seats 34 or 45.

The valve seat 45 is positioned between the cylinder air passage 37 and an atmospheric chamber 42 formed in the conical projection 14 on the shell 11. Exhaust ports 48 extend from the chamber 42 to the atmosphere.

A by-pass passage 49 extends from the cylinder air passage 37 upwardly through the housing 15, the wall of the shell 10 and through the plate 19 to the head plate 20, thence through a groove 50 to the cylinder 31.

In Fig. 8 the improved valve units are diagrammatically illustrated in a two-car train circuit. The valves are controlled by a brake control lever, indicated at 51, which can be swung to three positions, A, B, and C, A being the "running" position, B being the "primary braking" position, and C being the "secondary braking" position.

When the lever 51 is swung to the "primary" position, B, it closes a circuit with a contact bar 52, and when swung to the "secondary braking" position C, it maintains the circuit with the contact bar 52 closed and closes a second circuit with a braking contact 53. A source of current is indicated by the battery 54, one side of which is connected to the brake control lever 51. The other side of the battery is connected to a ground conductor 57. The braking contact 53 is connected to

a secondary braking conductor 56, and the contact bar 52 is connected to a primary conductor 55.

The three conductors 55, 56 and 57 run throughout the length of every car and are connected between the cars by means of suitable detachable plugs and receptacles, as indicated at 58.

At each car, one terminal of each of the solenoids 22 and 23 is connected to the ground conductor 57 by means of a ground lead 57'. The other terminal of the solenoid 22 is connected to the secondary braking conductor 56 by means of a lead 56'. The other terminal of the solenoid 23 at each car is connected by means of a lead 55' with the primary conductor 55.

15

Operation

Let us assume that the train is running and the control lever is in the "running" position A. All of the solenoids, both 22 and 23, on all of the cars are deenergized and the unit in each car is in the position shown in Fig. 1 of the drawing. The spring 35 is holding the valve 33 away from the seat 34, and the spring 43 is holding the double valve 44 against the auxiliary air seat 34 and away from the exhaust seat 45. Therefore, the brake cylinder of the car is open to the atmosphere through the passage 37, the valve seat 45, the atmospheric chamber 42, and the ports 48 so that the brakes are fully released.

20

Let us assume that it is desired to apply the brakes. The control handle 51 is moved to the "primary braking" position B. This closes a circuit through the contact bar 52 and the primary conductor 55 with all of the solenoids 23 on the train.

25

The solenoid 23 at each car attracts its armature 41 toward its field core 25. This draws the valve 44 away from the seat 34, thus opening a passage for the air from the auxiliary reservoir of the car through the passage 36, and the valve seat 34 to the cylinder air passage 37, and thence to the brake cylinder of the car. The opening movement of the valve 44 plunges it against the exhaust seat 45 to prevent the escape of cylinder air.

30

Let us assume that it is desired to apply the brakes. The control handle 51 is moved to the "primary braking" position B. This closes a circuit through the contact bar 52 and the primary conductor 55 with all of the solenoids 23 on the train.

35

The solenoid 23 at each car attracts its armature 41 toward its field core 25. This draws the valve 44 away from the seat 34, thus opening a passage for the air from the auxiliary reservoir of the car through the passage 36, and the valve seat 34 to the cylinder air passage 37, and thence to the brake cylinder of the car. The opening movement of the valve 44 plunges it against the exhaust seat 45 to prevent the escape of cylinder air.

40

Let us assume that it is desired to apply the brakes. The control handle 51 is moved to the "primary braking" position B. This closes a circuit through the contact bar 52 and the primary conductor 55 with all of the solenoids 23 on the train.

45

The solenoid 23 at each car attracts its armature 41 toward its field core 25. This draws the valve 44 away from the seat 34, thus opening a passage for the air from the auxiliary reservoir of the car through the passage 36, and the valve seat 34 to the cylinder air passage 37, and thence to the brake cylinder of the car. The opening movement of the valve 44 plunges it against the exhaust seat 45 to prevent the escape of cylinder air.

50

Let us assume that it is desired to apply the brakes. The control handle 51 is moved to the "primary braking" position B. This closes a circuit through the contact bar 52 and the primary conductor 55 with all of the solenoids 23 on the train.

55

The solenoid 23 at each car attracts its armature 41 toward its field core 25. This draws the valve 44 away from the seat 34, thus opening a passage for the air from the auxiliary reservoir of the car through the passage 36, and the valve seat 34 to the cylinder air passage 37, and thence to the brake cylinder of the car. The opening movement of the valve 44 plunges it against the exhaust seat 45 to prevent the escape of cylinder air.

60

Let us assume that it is desired to apply the brakes. The control handle 51 is moved to the "primary braking" position B. This closes a circuit through the contact bar 52 and the primary conductor 55 with all of the solenoids 23 on the train.

65

The solenoid 23 at each car attracts its armature 41 toward its field core 25. This draws the valve 44 away from the seat 34, thus opening a passage for the air from the auxiliary reservoir of the car through the passage 36, and the valve seat 34 to the cylinder air passage 37, and thence to the brake cylinder of the car. The opening movement of the valve 44 plunges it against the exhaust seat 45 to prevent the escape of cylinder air.

70

Let us assume that it is desired to apply the brakes. The control handle 51 is moved to the "primary braking" position B. This closes a circuit through the contact bar 52 and the primary conductor 55 with all of the solenoids 23 on the train.

75

The solenoid 23 at each car attracts its armature 41 toward its field core 25. This draws the valve 44 away from the seat 34, thus opening a passage for the air from the auxiliary reservoir of the car through the passage 36, and the valve seat 34 to the cylinder air passage 37, and thence to the brake cylinder of the car. The opening movement of the valve 44 plunges it against the exhaust seat 45 to prevent the escape of cylinder air.

is only necessary to move the control lever 51 to the running position A so as to de-energize all solenoids as previously described.

The improved electro-pneumatic valve may be used independently or in conjunction with the present triple valve systems. If used independently a train line must be maintained for keeping the auxiliary reservoirs fully charged at all times.

It is desired to call attention to the fact that all slide valves with their attendant friction have been completely eliminated.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. An electro-pneumatic valve for controlling the flow of air from an auxiliary reservoir to and from the air brake cylinder of a railway car comprising: a valve housing; an auxiliary air passage in said housing; a cylinder air passage in said housing; a double valve seat between said passages; a first valve positioned to seat on one side of said double valve seat to close the latter; a double valve member positioned to seat on the other side of said double valve seat to also close the latter; an exhaust valve seat in said cylinder air passage to open the latter to the atmosphere, said exhaust valve seat being positioned to be closed by said double valve when the latter leaves said double valve seat; spring means urging said double valve against said double valve seat; a first electro-magnetic means acting when energized to withdraw said double valve from said double valve seat and against said exhaust seat; pressure actuated means adapted to force said first valve to seat against said double valve seat; and second electro-magnetic means acting when energized to withdraw said first valve from said double valve seat.

2. An electro-pneumatic valve for controlling the flow of air from an auxiliary reservoir to and from the air brake cylinder of a railway car comprising: a valve housing; an auxiliary air passage in said housing; a cylinder air passage in said housing; a double valve seat between said passages; a first valve positioned to seat on one side of said double valve seat to close the latter; a double valve member positioned to seat on the other side of said double valve seat to also close the latter; an exhaust valve seat in said cylinder air passage to open the latter to the atmosphere, said exhaust valve seat being positioned to be closed by said double valve when the latter leaves said double valve seat; spring means urging said double valve against said double valve seat; a first electromagnetic means acting when energized to withdraw said double valve from said double valve seat and against said exhaust seat; a pressure cylinder; a by-pass passage conveying air from said cylinder passage to said pressure cylinder; a piston in said pressure cylinder, said piston being connected with said first valve to force the latter against said double valve seat when the pressure in said cylinder passage reaches a predetermined point; and a second spring means urging said first valve away from said double valve seat.

3. An electro-pneumatic valve for controlling the flow of air from an auxiliary reservoir to and from the air brake cylinder of a railway car comprising: a valve housing; an auxiliary air passage in said housing; a cylinder air passage

in said housing; a double valve seat between said passages; a first valve positioned to seat on one side of said double valve seat to close the latter; a double valve member positioned to seat on the other side of said double valve seat to also close the latter; an exhaust valve seat in said cylinder air passage to open the latter to the atmosphere, said exhaust valve seat being positioned to be closed by said double valve when the latter leaves said double valve seat; spring means urging said double valve against said double valve seat; a first electro-magnetic means acting when energized to withdraw said double valve from said double valve seat and against said exhaust seat; a pressure cylinder; a by-pass passage conveying air from said cylinder passage to said pressure cylinder; a piston in said pressure cylinder, said piston being connected with said first valve to force the latter against said double valve seat when the pressure in said cylinder passage reaches a predetermined point; and a second electro-magnetic means arranged, when energized to draw said first valve from its seat.

4. An electro-pneumatic valve for controlling the flow of air from an auxiliary reservoir to and from the air brake cylinder of a railway car comprising: a valve housing; an auxiliary air passage in said housing; a cylinder air passage in said housing; a double valve seat between said passages; a first valve positioned to seat on one side of said double valve seat to close the latter; a double valve member positioned to seat on the other side of said double valve seat to also close the latter; an exhaust valve seat in said cylinder air passage to open the latter to the atmosphere, said exhaust valve seat being positioned to be closed by said double valve when the latter leaves said double valve seat; a first electro-magnetic means acting when energized to withdraw said double valve from said double valve seat and against said exhaust seat; a pressure cylinder; a by-pass passage conveying air from said cylinder passage to said pressure cylinder; a piston in said pressure cylinder, said piston being connected with said first valve to force the latter against said double valve seat when the pressure in said cylinder passage reaches a predetermined point; a second spring means urging said first valve away from said double valve seat; and a second electro-magnetic means arranged, when energized to assist said second spring means to draw said first valve from its seat.

5. An electro-pneumatic valve for controlling the flow of air from an auxiliary reservoir to and from the air brake cylinder of a railway car comprising: a valve housing; an auxiliary air passage in said housing; a cylinder air passage in said housing; an atmospheric air passage in said housing; a first valve seat between said auxiliary passage and said cylinder air passage; a second valve seat between said cylinder air passage and said atmospheric air passage; a first valve positioned to close said first valve seat; a second valve positioned to alternately close said first valve seat and said second valve seat; spring means urging both valves toward said first valve seat; electro-magnetic means arranged to move either or both said valves away from said first valve seat; a pneumatic means actuated from the air pressure in said cylinder air passage for forcing said first valve against said first valve seat.

6. An electro-pneumatic valve for controlling the flow of air from an auxiliary reservoir to and

from the air brake cylinder of a railway car comprising: a valve housing; an auxiliary air passage in said housing; a cylinder air passage in said housing; an atmospheric air passage in said housing; a first valve seat between said auxiliary passage and said cylinder air passage; a second valve seat between said cylinder air passage and said atmospheric air passage; a first valve positioned to close said first valve seat; a second valve positioned to alternately close said first valve seat and said second valve seat; pneumatic means adapted to close said first valve to said first valve seat in consequence of air pressure in said cylinder air passage; a first cylindrical shell mounted on said housing about said first valve; a second cylindrical shell mounted on the opposite side of said housing in alignment with the second valve; a cylindrical solenoid in each shell; an armature axially moveable in each shell under the influence of said solenoid; and means connecting each armature with one of said valves.

7. An electro-pneumatic valve for controlling the flow of air from an auxiliary reservoir to and from the air brake cylinder of a railway car comprising: a valve housing; an auxiliary air passage in said housing; a cylinder air passage in said housing; an atmospheric air passage in said housing; a first valve seat between said auxiliary passage and said cylinder air passage; a second valve seat between said cylinder air passage and said atmospheric air passage; a first valve positioned to close said first valve seat; a second valve positioned to alternately close said first valve seat and said second valve seat; pneumatic means adapted to close said first valve to said first valve seat in consequence of air pressure in said cylinder air passage; a first cylindrical shell mounted on said housing about said first valve; a second cylindrical shell mounted on the opposite side of said housing in alignment with the second valve; a cylindrical solenoid in each shell; an armature axially moveable in each shell under the influence of said solenoid; means connecting each armature with one of

5

said valves; a first spring means urging said first valve away from said first seat; and a second spring means urging said second valve toward said first valve seat.

8. An electro-pneumatic valve for controlling the flow of air from an auxiliary reservoir to and from the air brake cylinder of a railway car comprising: a valve housing; an auxiliary air passage in said housing; a cylinder air passage in said housing; an atmospheric air passage in said housing; a first valve seat between said auxiliary passage and said cylinder air passage; a second valve seat between said cylinder air passage and said atmospheric air passage; a first valve positioned to close said first valve seat; a second valve positioned to alternately close said first valve seat and said second valve seat; a first cylindrical shell mounted on said housing about said first valve; a second cylindrical shell mounted on the opposite side of said housing in alignment with the second valve; a cylindrical solenoid in each shell; an armature axially moveable in each shell under the influence of said solenoid; means connecting each armature with one of said valves; a first spring means urging said first valve away from said first seat; a second spring means urging said second valve toward said first valve seat; and pneumatic means actuated from the air pressure in said cylinder passage and connected with said first valve to urge the latter against said first seat when the pressure in said cylinder passage reaches a predetermined point.
